UNITED STATES PATENT OFFICE.

MORRIS BECKER, OF CHICAGO, ILLINOIS, ASSIGNOR TO GARMENT PRESSING MACHINE CO., OF CHICAGO, ILLINOIS, A CORPORATION OF ILLINOIS.

FEEDING ATTACHMENT FOR BOILERS.

1,119,391.

Specification of Letters Patent.

Patented Dec. 1, 1914.

Application filed December 30, 1911. Serial No. 668,626.

To all whom it may concern:

Be it known that I, MORRIS BECKER, a citizen of the United States of America, and resident of Chicago, Illinois, have invented 5 a certain new and useful Improvement in Feeding Attachments for Boilers, of which the following is a specification.

My invention relates to a boiler, and more particularly to an attachment for feeding. 10 Heretofore it has been necessary, in feeding water to a boiler, to employ an ejector or some means to feed this water under pressure to the boiler. By my improved construction, however, I provide means where- 15 by the boiler itself supplies the requisite pressure for forcing the feed-water into the boiler under pressure. I am thus enabled to do away with the use of an injector or any pump for forcing the water under pressure into the boiler. These and other ob- 20 jects of my invention will be more readily understood by reference to the accompanying drawings, in which—

Figure 1 is a perspective view of a boiler 25 embodying the features of my invention. Fig. 2 is a longitudinal sectional view of the same. Fig. 3 is a sectional view taken upon line 3—3 of Fig. 2.

As illustrated, my boiler comprises an 30 outer cylindrical shell 4 within which is located a cylindrical tube 5 extending the entire length of the shell 4. The bottom plate 6 is securely riveted to the shell 4 while the boiler-head 7 is secured to the top of the 35 shell. Located at a distance below the boiler-head 7 there is a second boiler-head 8. This second boiler-head divides the boiler into a main compartment 9 and an auxiliary or feed-water compartment 10. 40 Located inside the tube 5 there is a super- 45 heater 11. This superheater comprises an elongated tube through which the steam passes downward through the passage 12, and then upward through the passage 13 and thence to the outlet pipe 14. This 50 superheater is connected with the upper or main compartment 9 by means of the pipe 15. Likewise connected to the upper portion of this main compartment 9 there is a 55 second pipe 16 which passes through the boiler-head 7, and thus communicates with the upper portion of the feed-water compartment 10. Connected at a point near the bottom of this feed-water compartment 10 there is a feed-pipe 17 which communica-

cates through a suitable valve 18 with the lower part of the main compartment 9. Suitable pressure gages 19 and 20 are associated with the two compartments in the usual manner, in order to indicate the respective pressures maintained in these compartments. A safety valve 21 is likewise connected with the compartment 9.

Heat is supplied to the boiler by means of the gas burner 22, which is located below the boiler, the boiler being supported upon legs 23 to provide space for this burner.

Suitable valves 24 and 25 are provided in the feed pipes 16 and 17, respectively, so as to regulate the feed to the boiler.

In the operation of my boiler, the valve 26 in the feed pipe 27 is opened to permit water to pass into the upper feed-water compartment 10, and then passes from this compartment through the feed pipe 17 and valve 18 into the main compartment 9. As heat is applied to the boiler, the pressure within the compartment 9 increases, and in order to feed the boiler at this time it is necessary that the water be forced into the same under pressure. By my invention I provide this pressure by means of the by-pass feed-pipe 16. The steam passing through this pipe, the amount of which can be regulated by means of the valve 24, enters the top of the 80 compartment 10. This steam entering this compartment exerts a pressure upon the surface of the water, which produces sufficient pressure to force the water from this compartment through the pipe 17 into the main 85 compartment 9. But a small quantity of steam generated in the compartment 9 passes through the by-pass 16, the greater portion passing through the pipe 15 to the superheater 11 to the main outlet pipe 14.

In operation, I find it advisable to first close the valve 25 in the pipe 17 and the valve 24. I then open the valve 26 in the feed-pipe 27 which is connected to the city main. When the feed-water compartment 100 has become filled, I close the valve 26 to prevent the water from backing up into the city main. I then open the valves 24 and 25. The steam passing through the pipe 16 exerts a pressure on the surface of the water 105 in the compartment 10, which thus forces the water under pressure through the pipe 19 to the lower compartment 9 of the boiler. In practice the valve 25 is opened just sufficiently to feed the requisite amount of water 110

to the boiler. That is, the amount of water fed to the boiler equals the amount turned into steam. As the pressure in the boiler increases, the pressure of the steam passing 5 through the pipe 16 increases so that the pressure of the feed water automatically increases with the increase of pressure in the boiler.

It is thus seen that I have devised a very 10 efficient and simple mechanism for a boiler feed, and one in which it is unnecessary to employ a special injector or other pump for forcing the water under pressure into the boiler.

15 While I have illustrated one particular type of my invention, it will be understood that I do not wish to limit myself to such exact construction.

20 What I claim as my invention is:
In a boiler, a cylindrical shell, a boiler-

head at the top of said shell, and a second boiler-head located at a distance below said first boiler-head to thereby divide said boiler into two compartments, a steam pipe communicating with the upper portion of the 25 lower compartment and extending to and communicating with the extreme upper portion of the upper of said compartments, and a feed-water connection extending from the lower portion of said upper compartment 30 and communicating with said lower compartment, an outlet pipe, and an independent connection from the upper portion of said lower compartment to said outlet pipe.

Signed by me at Chicago, Illinois, this 35
12th day of December, 1911.

MORRIS BECKER.
